UNITED STATES PATENT OFFICE.

MARTIN V. B. ETHRIDGE, OF BOSTON, MASSACHUSETTS, ASSIGNOR OF TWO-THIRDS TO JOHN SWANN, OF NEW YORK, N. Y., AND HENRY E. WAITE, OF WEST NEWTON, MASSACHUSETTS.

TIME-PIECE DIAL.

SPECIFICATION forming part of Letters Patent No. 394,845, dated December 18, 1888.

Application filed January 18, 1888. Serial No. 261,079. (No model.)

To all whom it may concern:

Be it known that I, MARTIN V. B. ETHRIDGE, a citizen of the United States, residing at Boston, in the county of Suffolk and State of Massachusetts, have invented certain new and useful Improvements in Time-Piece Dials; and I do hereby declare the following to be a full, clear, and exact description of the invention, such as will enable others skilled in the art to which it appertains to make and use the same.

My invention refers to that class of time-piece dials having a radial series of intermittently-rotary spindles carrying numeral-blocks and designed to indicate the time from one to twenty-four hours each day; and the invention consists in the construction and combination of mechanical devices which operate automatically to shift or turn the entire series of spindles in unison at the end of each and every period of twelve hours, said mechanism acting in such a manner as to turn the spindles in a forward direction at each movement.

A companion application filed of even date herewith, Serial No. 261,078, comprises automatic mechanism which works in such a manner as to turn the spindles in a forward direction at one movement and in a backward direction at the other movement, each alternate movement being in a direction the reverse of its predecessor; but the present case covers mechanism which automatically operates at the end of every period of twelve hours to shift or turn the spindles forward, so that said spindles have a continuous forward movement instead of an alternate forward and backward movement; and the invention further includes certain details and peculiarities in the construction, arrangement, and combination of the several parts, whereby the end in view is accomplished, substantially as will be hereinafter fully described and claimed.

In the annexed drawings, Figure 1 represents a front elevation of my improved mechanism for automatically shifting the spindles, and Fig. 2 is a top plan view of the same. Fig. 3 is a plan view of a series of spindles with my invention applied thereto.

Like letters of reference designate like parts in all the figures.

A represents a large gear suitably toothed and properly sized to adapt it to perform the same purpose which is attributed to the large gear A in the companion application above referred to. The gear A is loosely mounted in a vertical position upon the same hollow arbor, b, surrounding the hour-hand sleeve, as that in which the inner ends of the spindles (shown in Fig. 3) are journaled; hence it will be seen that the said gear is free to turn upon a fixed support.

To the rear side of the gear A is rigidly secured a ratchet-wheel, S, concentric with said gear, but of less diameter. In the rear of the gear A, between it and the clock-plate U, a gear, F, is pinned or otherwise securely fastened to the hour-hand sleeve. This gear F meshes with and drives a gear, G, which is suitably mounted upon a stud projecting from the plate U. The outer face of the gear G has fastened rigidly thereto a cam, H, having a curved outline, which is parallel to the circumference of the gear G, said outline terminating in an upper point, K, and a lower point, N, the lower point being opposite to the upper and beneath it when the gear is in the position shown. The points K and N of the cam, in addition to being connected by the symmetrically-curved outline thereof just referred to, are also connected by an irregular outline on the other edge of the cam. The gear F, as also the gear G, revolves once in twelve hours.

P denotes a lever fulcrumed upon the same support as gear A. The lever P extends for some distance on opposite sides of its support. One end of it carries a weight, D, which is normally stationary, but may be adjusted by means of a set-screw, as shown. The other end carries a weight, B, which is arranged to slide or reciprocate thereon between the outer extremity of the lever and its fulcrum. The portion of the lever P which carries the weight D is peculiarly shaped to permit it to be provided with pins L and M, which project outward therefrom and at a suitable distance apart, as will be perceived from inspection of Fig. 1.

The cam H during the revolution of the gear G, to which it is attached, moves in contact with the pins L and M on the lever P. Furthermore, the cam is connected with the 5 sliding weight B by means of connecting-rod I, pivoted at one end to the cam and at the other to the weight, said rod being preferably in the form of a frame, as shown, which surrounds the collar and hour-hand sleeve.

10 The lever P carries a hook or pawl, R, which is held in engagement with the ratchet S by means of a spring bearing against it, and said hook-pawl is so arranged as to exert a downward pressure upon one of the teeth of the 15 ratchet-wheel, and can be fed forward from one tooth to the other during the movement of the lever P. A retaining-pawl, T, fastened to a suitable support, engages the ratchet S and keeps it from moving in a direction the reverse of that in which it is fed by the hook-pawl R.

I have now described the essential features of the construction of my improved mechanism, and it remains to briefly sketch the operation of the mechanical parts.

The lever P is caused to rock upon its fulcrum, and the rocking movement of the lever, through the intermediate agency of the hook-pawl and the other parts, rotates the gear A 30 sufficiently far forward at the end of each period of twelve hours to rotate the spindles and display different numerals to view from those displayed during the preceding twelve hours. The gear G will revolve, as already 35 stated, under the actuating impulse of the gear F, and in its revolutions will carry with it the cam H, the edge of which is in contact with the pins upon one end of the lever.

In Fig. 1 the parts are shown in the position 40 where the point K of the cam has just been released from the pin L, thus permitting the latter to drop, because the connecting-rod I has drawn the weight B to its innermost position, and hence the end of the lever carrying the weight D is heavier than the end carrying the weight B, and when the cam no 45 longer holds up the heavier of these ends it must necessarily fall under the action of gravity. The falling of the end of the walking-beam which carries the weight D will cause the other end thereof to be elevated and the hook-pawl R to be lifted from one notch of the ratchet S into the next notch. Suppose, now, 50 the cam to continue revolving from the point we have just seen it occupying in Fig. 1. The point N will pass over the pin M and the cam will ride upon said pin until the point K has reached the pin M, when it will be released from said pin, and at the same time that the 55 point K ceases to act on pin M the weight B will have been pushed to its outermost position on the lever P, causing the end of the lever P which carries the weight B to overbalance the opposite end, and as the cam does 60 not longer act upon the pin M to hold the end of the lever P down said end will go up, while the other end, carrying the weight B, goes

down, and at the same time the hook-pawl R pulls the ratchet around, and the gear attached to said ratchet is consequently rotated 70 sufficiently far to shift the spindles. It will be seen that if this operation continue the end of the lever P which carries the hook-pawl R will be lifted once in every six hours and will fall back at the end of the next six 75 hours, thus causing the gear A to be rotated once at the end of every twelve hours and the spindles shifted. As the result, therefore, of the automatic mechanism herein described and operating as set forth the spindles will 80 be rotated continuously forward by means of a series of intermittent rotations occurring at the end of every twelve hours.

Having thus described my invention, what I claim as new, and desire to secure by Letters 85 Patent, is—

1. In a time-piece dial having a series of radial spindles, the combination of a rotative gear connecting with the spindles and provided with a circular ratchet, a rocking lever 90 fulcrumed behind the gear and carrying weights on its opposite ends, and a finger or hook-pawl on the lever to engage the ratchet, together with mechanical devices for adjusting the weights to cause the lever to rock and 95 the gear thus to revolve and shift the spindles, substantially as described.

2. In a time-piece, the combination, with a radial series of spindles, of a rotative gear connecting with the spindles and provided 100 with a circular ratchet, a rocking lever fulcrumed behind the gear and carrying weights on the opposite ends and a hook-pawl which engages the ratchet, one of said weights being normally stationary and the other adapted to 105 slide, and mechanism for moving the sliding weight relatively to the other, so that the lever may rock in the manner described, and thus cause the gear to revolve and the spindles to be shifted, substantially as herein set 110 forth.

3. In a time-piece, the combination of a series of radial spindles, a rotative gear connecting with the spindles and provided with a circular ratchet, a rocking lever fulcrumed 115 behind the gear and carrying weights on its opposite ends, a finger on the lever which engages the ratchet, and mechanism for adjusting the weights so as to rock the lever, consisting of a cam, a link-connection between it 120 and one of the weights, and a gearing-connection between the cam and the time-piece movement, all substantially as set forth.

4. In a time-piece, the combination of a series of spindles, a rotative gear connecting 125 with the spindles and provided with a circular ratchet, a rocking lever fulcrumed behind the gear and carrying weights on its opposite ends, a pawl on the lever which engages the ratchet, and a rotating cam operated by connection with the time-piece mechanism and acting upon projections or pins on one end of the lever while it connects with and causes the weight upon the other end of said lever to 130

slide thereon, all the parts operating to accomplish a rocking of the lever and a partial rotation of the ratchet and its attached gear at stated intervals, substantially as described.

5 5. In a time-piece dial having a series of radial spindles, a gear-wheel, A, provided with a ratchet, S, a rocking lever, P, fulcrumed behind the gear and carrying weights B and D, and also a hook-pawl, R, which engages the 10 ratchet S, the cam H, the connecting-rod I, and

the gearing which actuates the cam and causes it to operate, substantially in the manner hereinabove described.

In testimony whereof I affix my signature in presence of two witnesses.

MARTIN V. B. ETHIRIDGE.
